SERVING-HATCHWAY AND THE LIKE

Karl Osten Schauman, Hampton Wick,
EnglandApplication October 4, 1930, Serial No. 486,473,
and in Great Britain November 15, 1929.

2 Claims. (Cl. 20—1.11)

The invention refers to hatchways through which dishes and the like are served from the rooms where they are prepared to the rooms where they are consumed and has for its object 5 the prevention of cookery smells, steam, noise and the like penetrating from the former into the latter rooms.

Hatchways are very generally adopted in mansions, restaurants, hotels and the like for the purpose of shortening the time of conveying courses or dishes from kitchens to dining rooms, particularly where these are situated on the same floor and only separated by one or two easily pierced walls, so that without a hatchway the trays 10 would have to be carried around and along one or more passages. Hitherto such hatchways suffered from the drawback that during use the hatchway aperture stood open, sometimes even disclosing a vista of the kitchen and in all cases 15 merely one dividing wall remained interposed between kitchen and dining-room during use thus allowing the smells and noises to pervade the eating rooms.

The invention broadly consists in providing 20 simple means for keeping always at least two walls interposed independent of whether the hatchway stands open at the kitchen side or on the dining room side, and other means for the same purpose hereafter described. The preferred construction to perform this automatically is described and shown in the annexed drawings of which:

Fig. 1 is a sectional elevation with a portion of the wall broken away.

Fig. 2 is a sectional elevation with the drawer partly pulled out.

Fig. 3 is a front elevation with drawer closed.

Fig. 4 is a front elevation with drawer open.

Fig. 5 is a plan showing connecting wires.

40 In the dividing wall *e* between kitchen and dining room is cut a square or like aperture which is lined with a fixed frame *V* to receive a movable drawer *W*. A pair of outwardly swinging doors or flaps *a* are hinged to the frame at each side 45 thereof, and related doors of the respective pairs are connected one with the other by a wire *o* extending over guide sheaves *r* the ends of the wires being attached to the doors short distances from their hinges, so that when either door of a pair 50 is opened the related door of the other pair necessarily is closed. Preferably interposed in each wire *o* is a spring *m* to effect cushioning of the doors when they are swung outward.

The drawer *W* is supported on a pair of horizontal rods *g* one at either side thereof suitably

fixed to the frame, the drawer carrying tubes *h* suitably secured thereto as at *i* and slidably engaged on said rods.

The drawer which may be of any convenient shape may advantageously be divided into several tiers or compartments for instance a lower or cold compartment *d* and an upper or hot compartment *c* and in this case a hot plate *f* of copper or the like is provided to form the bottom of the hot compartment, and electric elements may be arranged underneath this plate in known manner for the purpose of creating or maintaining a certain desired temperature. The walls of the drawer or moving tray may be of metal or metal lined *l* and are packed with asbestos *k* or any preferred material of low thermic conductivity and an extra thick layer thereof is arranged beneath the heating elements so as to prevent loss of heat to the upper and access of heat in the lower tier.

The electric heater or heaters *n* may receive current by a contact spring rubbing on a metal bar fixed on each side of the frame, when these bars are brought into circuit with a source of current by a switch (not shown) placed at the side of the drawer.

The drawer is provided with top and bottom flaps *c'*, *d'*, respectively, at each end thereof controlling access to the respective compartments *c* and *d*, said flaps being mounted for either swinging or sliding movement to open and closed positions. Handles *j* are provided on the flaps for facility in opening and closing the same and for sliding the drawer into and out of the frame *v*, while pads *q* of suitable material are provided on the drawer sides to deaden any sound which otherwise might result from sliding the same into and from said frame. Moreover, one of the doors *a* of each pair preferably is provided along its free edge with a strip *s* to overlie the free edge of the other door of the pair when said doors are closed to provide for the effective sealing of the joint between the edges of the doors of each pair.

The length of the drawer *W* is only slightly 100 less than the distance between the doors *a* at either side of the wall *e* when said doors are closed. Thus, it follows that the doors or flaps of the drawer must be closed after the drawer is pushed into the hatchway from either side 105 thereof to permit closing of the doors *a* at that side of the hatchway and opening of the doors *a* at the opposite side thereof. Consequently it follows, due to the further fact that the doors *a* at either side of the hatchway cannot be opened 110

without closing the doors *a* at the other side thereof, or unless the doors *a* at the other side thereof are closed, that a barrier always exists preventing the direct passage of noise, fumes or the like from one side to the other side of the wall through the hatchway.

In the use of the device the doors *a* at one side of the hatchway are opened to permit the drawer *W* to be partly withdrawn if desired. The flaps or doors at the thus exposed end of the drawer then are opened to permit the desired dishes or other articles to be placed within the drawer. The drawer flaps or doors then are closed and, if the drawer was partly withdrawn from the hatchway, it is pushed back into the same. The doors *a* then are closed to permit the doors *a* at the other side of the hatchway to be opened, or closing of the first mentioned doors *a* may be effected by opening of the doors *a* at the other side of the hatchway. In either event opening of the latter doors exposes the other end of the drawer so that the same may be withdrawn and its contents removed by opening the flaps or doors at the second end thereof.

It is obvious that other means than those shown in the example illustrated may be substituted for ensuring the closing of the kitchen hatch-door ere the dining room hatch-door can be opened, without deviating from the invention.

For cases where kitchen and dining room are

not directly adjacent and the drawer may have to travel a long path, not necessarily straight, the construction may be adapted without abandoning its characteristic features.

What I claim is:—

1. In combination with means having a passageway formed therethrough, an outwardly opening door at each end of said passageway, and means connecting said doors together so that when either door is fully open, the other door must be closed and whereby, when either door is open, opening of the closed door effects closing of the open door.

2. In combination with a wall having an opening formed therethrough, an outwardly swinging door at each end of said opening, means connecting said doors together so that when either of the same is fully open the other must be closed and whereby, when either door is open, opening of the closed door effects closing of the open door, a receptacle slidably within said opening, and corresponding substantially in cross sectional area to the cross sectional area of the opening, and doors at the ends of said receptacle, said receptacle approximating in length the distance between said first mentioned doors when the latter are closed whereby the doors of said receptacle must be closed to permit opening and closing of the said first mentioned doors.
